ROAD PLANERS AND THE LIKE

Ralph W. Bond, West Springfield, Pa.

Application January 12, 1953, Serial No. 330,851

13 Claims. (Cl. 37—150)

This invention relates generally to road repairing machines and more particularly to road planers for leveling the aggregates such as gravel, stone, or earth to level the same preparatory to rolling and for repair work for cutting off high places in earth and gravel roads and filling in depressions and holes, leaving a smooth and accurate surface on the road.

In road maintenance equipment, it has long been a problem to support the blades of the maintenance equipment in such manner that they are readily adjustable to various road contours. Hydraulic jacks have been tried to adjust the ends of the blades and the runners which rest on the ground and carry the blade rigidly supported therebetween but these were found to be unsatisfactory. It has also been a problem in the use of road planers to clear the blades of large bunches of earth, rock, and trash that sometimes pile up in front of the blades.

It is, accordingly, an object of my invention to provide a blade supporting mechanism for a road maintenance machine which will support the blade in a manner that the blade will adjust itself to various road surfaces.

Another object of my invention is to provide a novel frame for road maintenance equipment.

Another object of my invention is to provide a novel type of reinforcement for a blade for a road maintenance machine.

Another object of my invention is to provide an implement to be used in construction and repair maintenance of roads constructed of earth, gravel, and other surfaces.

Another object of the invention is to provide a road planer or maintenance machine which is simple in design, durable in construction, and easy to operate.

Another object of the invention is to provide a road maintenance machine or planer which may be controlled by one operator and drawn by one tractive unit.

Another object of the invention is to provide a novel type of tractive unit hitch which will enable the blades of a road maintenance machine or planer to clear themselves of obstruction when the implement is backed up.

With the above and other objects in view, the present invention consists of the combination and arrangement of parts hereinafter more fully described, illustrated in the accompanying drawings, and more particularly pointed out in the appended claims, it being understood that changes may be made in the form, size, proportions, and minor details of construction without departing from the spirit or sacrificing any of the advantages of the invention.

In the drawings:

Fig. 1 is a plan view of a road maintenance machine according to my invention;

Fig. 2 shows a side view of the machine shown in Fig. 1;

Fig. 3 shows a detailed enlarged view of one of the elements of the machine shown in Figs. 1 and 2;

Fig. 4 shows an enlarged front view of part of the frame of the machine shown in Figs. 1 and 2;

Fig. 5 shows another embodiment of my road planer showing a novel type of blade supporting means;

Fig. 6 shows a side view of the device shown in Fig. 5;

2

Fig. 7 shows a novel blade reinforcement; and Fig. 8 is a view of part of the blade supporting means shown in Fig. 7.

Now with more specific reference to the drawings, Fig. 5 1 shows a road maintenance machine having a main frame 1 and a blade supporting A-frame 2 supported on the main frame. The main frame is supported on the axle 3. Axle 3 is carried by wheels 4. The hitch 5 is pivotally connected to the main frame at 76 and adapted 10 to be connected to a tractive unit by clevis 71.

The main frame is made up of two spaced parallel runners 11 and 12 connected at the front by arch 13 and at the rear by angle member 14 which is attached to axle 3 through angle irons 15. Angle irons 15 are attached 15 to angle member 14 at 16 by welding or other well known fastening means and are fastened to runner 11 at 17 and to runner 12 at 18 in a similar manner. Axles 3 are journaled in wheels 4 on hubs 19 in the conventional manner.

20 The axles 3 are located at a predetermined distance rearward of the runners 11 and 12 and the vertical distance between the bottom surface 21 of the runners and the bottom edge of the tire 30a may be adjusted by deflating or inflating the tires 22. This will cause the 25 effective diameter of the wheels 22a to change and the weight of the frame carried by the runners can be adjusted in this manner. In other words, by increasing the pressure in the tires, the hubs will be raised and the weight carried by the axle 3 will be increased and, thereby, decrease the wear on the runners. The depth that the blades cut into the road will also be decreased. Therefore, the draft required to draw the planer and the side slip of the planer can be regulated. By increasing the inflation of the tires, the rear end of the runners can 35 be forced to clear the ground.

The A-frame is supported on the main frame by the support member 30 shown in detail in Fig. 3. The A-frame is made up of rigid angular members or channels 23 attached together by longitudinal braces 24 connected 40 to the rearward member at 25 and the forward member at 26 by welding, riveting, or other means. The support for the A-frame is shown in Fig. 3 and is made up of the rod 31 which has the bottom thereof bent to pass through a hole 32 in the member 23 which is attached to the blade. The rod 31 extends upwardly through a hole 33a in bracket 36 through spring 33 and through washer 34. Nut 35 is provided on rod 31 to engage the top of washer 34. The bottom part of the helical spring 33 rests on the bracket 36 which is bent at 37 at right angles and extends downwardly and is attached to the main frame at 38. The vertical leg 39 of the runner is provided with a slot 40 through which bolt 41 extends. Angular lever 42 is pivoted to the vertical leg 39 of the runner member at 43 and has the bolt 41 extending therethrough. The front end of the lever member 42 has a hole 44 therethrough and bolts 45 extend through the hole 44 and terminate at the lower end thereof in the right angular hook portion 46 which engages a hole 47 in ear 48. Ear 48 is attached to the horizontal leg of the runner angle at 49. The nut 50 is welded to the tubular portion 51 at 52 and the tube 51 is welded to the lever 53 of the handle at 54 and 54a. A section of pipe 55 loosely engages the horizontal leg of the lever at 56 and loosely engages the nut 50 at 57 in such manner that the lever 53 can be rotated freely without rotating the tubular member 55. The horizontal lever 53 of the crank is provided with a hand engaging portion 58 which has the dual function of being a hand engaging portion and also a counterweight. It will be noted in Fig. 2 that the support 30 and bolt 45 are inclined from a vertical position. 60 By virtue of the fact that the support member 30 and bolt 45 are disposed at an angle and hand portion 58

acts as a counterweight, the nut 50 is caused to bind on the thread and thereby prevent movement of the nut relative to the bolt 45.

From the description of Fig. 3, it will be seen that the A-frame may be supported by the apex 60 and the ends 61 and 62 by supporting assemblies. When the runners are in contact with the ground and the blade 61 is clear of the ground, the A-frame is supported by the spring 33 and is suspended freely therefrom. The bolt 41 slides freely in the slot 40 and the tube 55 is out of engagement with the lever 56. When the cutting edge of the blade engages the surface of the road, the A-frame will be forced upward until the front end of the lever 42 is forced up until it engages the tube 55 and pushes it into engagement with the nut 50. When the lever 42 engages pipe 55 and nut 50, the blade will be held against further vertical movement. Any further vertical movement of the blade will require that the runners be raised with the blade. When the runners are in contact with the ground and the planer passes over a depression in the ground, the A-frame will drop downward and be supported by the spring 33 through the rod 31. When it is desired to merely "skin" the surface of the road with the blade, the main frame can be raised by extending cylinder or jack 80 to support the frame between the hitch 5 and axle 3. A-frame 2 will then be suspended on spring 33.

The runners are held together at the front thereof by the arch member made up of the horizontal angle iron 65 which is welded to the lateral member 66 at 67 and the hitch 5 passes under the arch member. The hitch is made up of the draw bar engaging member 70 which has members 71 for attaching to a draw bar of a tractive machine and bell crank 72 is pivoted to the member 70 at 73 forming a vertical leg 74 and angularly disposed leg 75. The leg 75 is pivoted to the runner at 76 by a pin which passes through a hole in the runner. The vertical leg 74 is pivotally connected to the piston rod 81 of the hydraulic cylinder 80 at 77 and the hydraulic cylinder is pivoted to the links 70a of the draw bar engaging member 70 at 82. The links 70a are preferably made of an angle iron and the horizontal leg rests on the horizontal leg of the member 70 at 70b. The hydraulic cylinder is provided with fluid under pressure from the pressure system of the tractive machine which pulls the planer.

The height of the planer above the road is controlled by means of the hydraulic cylinder 80. When it is desired to lift the planer from the road, fluid under pressure is applied to the cylinder 80 which causes the piston rod to rotate the bell crank clockwise around pivot 73 and this will require leg 75 to raise the front end of the planer off of the road.

Leg member 75 forms a bifurcated figure and extends laterally to engage the runners. When it is desired to transport the planer, the hydraulic cylinder is expanded and the planer is carried between the hitch 5 and the axle 3. When it is desired to merely scrape the surface of the road, the hydraulic cylinder is retracted, thereby somewhat lowering the runners to allow the cutting edge of the blade to engage the road without allowing the surface 21 to engage the surface of the road.

If the cutting edges of the blades become blocked by an abnormal amount of dirt or trash in front of them, the planer can be raised by backing the truck or tractive machine. A rearward force on the member 71 of the draw bar engaging member 70 will cause the main frame and member 75 to jackknife about point 76, causing the front part of the planer to raise off the ground and, consequently, the blades will be raised to clear the obstruction. This is a novel feature which is inherent in the design of my novel planer.

Adjustment of the height of the A-frame and, thereby, the depth of cut of the cutting edges is obtained by rotating the lever 53 of the member 30 to force the front

end of the lever 42 downward and, thereby, force the blade downward with regard to the runners. The tube 55 performs the dual purpose of being a force transmitting means and enclosing the threads to protect them from dirt, dust, and weather and to retain lubrication.

By the combination of the spring suspended blade with the positive force exerted by the tube 51, a reliable adjustment is provided which is free from lost motion and chatter and which has considerable strength in all the parts.

An enlarged view of the manner of attaching the blade to the angle irons or channels 23 is shown in Fig. 7. The cutting member of the blade is attached to the channel 23 by means of the bolts 62a which are welded to the point of junction of the angle 63 with the legs 64 and 65a joined. The bolts are threaded at 66a to receive nuts 67a. The bolts 62a pass through holes 68 on the members 23. When the bottom portion of the blade 61a wears down, the bolts 62a can be put through the holes 70a, thereby lowering the cutting portion of the blade and increasing the life thereof. The angle 63 does not form an obstruction to the movement of earth in front of the blade. Conversely, the dirt slides up along the front edge of the blade and is rolled over by the angle, actually improving the action of the blade. The channel 23 is bent in a concave manner at 68a to form a recess for the blade 61a to deflect into when the bolts 62a are tightened.

Another embodiment of the invention is shown in Figs. 5 and 6. The A-frame 102 is supported on the main frame 101 by means of a structure similar to that shown in Fig. 3. However, instead of the spring arrangement, a counterweight arrangement is provided. The blades 160 are attached to members 123 in a similar manner to that shown in Figs. 1 and 7. A lever 142 is pivoted to the main frame at 143 and to the A-frame at 146. Counterweight frame 133 is balanced on the end of the lever at 156. Similar levers are pivoted at the other two terminals of the A-frame. It will be seen that when the weight in the weight box 134 is increased, the tendency for the A-frame carrying the blade to be raised from the ground is increased.

In the foregoing specification, I have set forth the invention in its preferred practical forms but I am aware that the structure shown is capable of modification within a range of equivalents without departing from the invention which is to be understood as broadly novel as is commensurate with the appended claims.

What I claim is:

1. A road planer comprising a main frame comprising two parallel ground engaging runners, a blade supporting frame supported on said main frame, means to support said blade supporting frame on said main frame, said supporting means comprising a lever pivotally mounted on said main frame and pivotally connected to said blade supporting frame at a point spaced from said main frame pivotal point, means to adjustably limit the upward movement of one end of said lever, said means to limit the upward movement engaging said lever at a point spaced from the pivotal connections whereby the upward movement of said blade supporting frame is adjustably limited with regard to said main frame, and resilient means to urge said blade supporting frame upward.

2. The road planer recited in claim 1 wherein the adjusting means comprises a bolt attached to said main frame and extending through a hole in said lever, a nut disposed on said bolt attached thereto, and a section of pipe disposed between said nut and said lever, said section of pipe and said nut being disposed on said bolt on a side of said lever remote from the connection of said bolt with said main frame.

3. The road planer recited in claim 2 wherein said bolt is disposed at an angle with respect to a vertical line, a handle is attached to said nut, and a counterweight is provided on said handle whereby the threads on said nut are caused to bind on the bolt thread.

4. The road planer recited in claim 2 wherein a piece of pipe is welded to said nut and telescopically disposed on said bolt on the side remote from said section of pipe and a handle is connected to said piece of pipe.

5. The road planer recited in claim 1 wherein the adjusting means comprises a bolt attached to said main frame and extending through a hole in said lever, a nut disposed on said bolt attached thereto, a section of pipe disposed between said nut and said lever, said section of pipe and said nut being disposed on said bolt on a side of said lever remote from the connection of said bolt with said main frame, and a bracket attached to said main frame.

6. The road planer recited in claim 5 wherein a handle is attached to the nut.

7. The road planer recited in claim 6 wherein a counter-weight is attached to the end of the handle whereby the nut is caused to bind on the bolt, thereby preventing the nut from rotating on the bolt.

8. The road planer recited in claim 5 wherein said blade supporting frame comprises two blade supporting members disposed at an angle to each other and the frame is supported at each end by one adjusting means.

9. A road planer comprising a main frame comprising two parallel ground engaging runners, a blade supporting frame supported on said main frame, means to support said blade supporting frame on said main frame, said supporting means comprising a lever pivotally mounted on said main frame and pivotally connected to said blade supporting frame at a point spaced from said main frame pivotal point, means to adjustably limit the upward movement of one end of said lever, said means to limit the upward movement engaging said lever at a point spaced from the pivotal connections whereby the upward movement of said blade supporting frame is adjustably limited with regard to said main frame, resilient means to urge said blade supporting frame upward, one end of said main frame having a hitch pivotally attached thereto, said hitch comprising a draw bar engaging member, a link pivoted to said draw bar engaging member at an intermediate point on said link, said link being pivoted to said main frame at one end of said link, an extendable link attached to the other end of said link and to said draw bar engaging member, and means on said main frame engaging said link to limit the downward movement but allow free upward movement thereof, the end of said main frame opposite said hitch being supported by two ground engaging wheels.

10. A road planer comprising a main frame comprising two parallel ground engaging runners, a blade supporting frame supported on said main frame, means to support said blade supporting frame on said main frame, said supporting means comprising a lever pivotally mounted on said main frame and pivotally connected to said blade supporting frame at a point spaced from said main frame pivotal point, means to adjustably limit the upward movement of one end of said lever, said means to limit the upward movement engaging said lever at a point spaced from the pivotal connections whereby the upward movement of said blade supporting frame is adjustably limited with regard to said main frame, resilient means to urge said blade supporting frame upward, one end of said main frame having a hitch pivotally attached thereto, said hitch comprising a draw bar engaging member, a link pivoted to said draw bar engaging member at an intermediate point on said link, said link being pivoted to said main frame at one end of said link, an extendable link attached to the other end of said link and to said draw bar engaging member, and means on said main frame engaging said link to limit the downward movement but allow free upward movement thereof, the end of said main frame opposite said hitch being supported by two ground engaging wheels, said hitch being connected to said main frame at a point below said draw bar engaging member whereby when said draw bar engaging member is moved backward, said main frame is free to be lifted to clear obstructions of

foreign material accumulated under said blade supporting frame.

11. The road planer recited in claim 1 wherein said resilient means to urge said blade supporting frame upward comprises coil compression springs attached to said main frame and to the ends of said blade supporting frame, said compression springs supported on said main frame, a rod extending through said compression springs and having means supported on said rod on the end of said springs remote from said runners, said rod being pivotally connected to said blade supporting frame at the lower end thereof below said compression springs, said blade supporting frame compressing said compression springs when said blade is not supported by a surface to allow said blade supporting frame to extend below said main frame when said blade supporting frame is not supported by a supporting surface.

12. A road planer comprising two generally parallel spaced, longitudinally extending runners, said runners being rigidly connected together, an A-shaped frame with each leg of the A frame having a cutting member attached to the lower forward edge adapted to engage the surface of a road, the apex of said A-shaped frame and the end opposite said apex of each said leg having coil compression springs attached thereto, said compression springs supported on said runners at the lower end thereof, a rod extending through said compression springs and having means supporting said rod on the end of said springs remote from said runners, said rod being pivotally connected to said A-shaped frame at the lower ends thereof below said compression springs, said A-shaped frame being adapted to compress said compression springs to have its lower edge extend below the lower surface of said runners when unsupported by engagement with a road surface or other supporting surface, means to limit the upward movement of said A-shaped frame, the rear end of each of said runners being supported by wheels and the front end having a tongue attached thereto, said tongue comprising a bell crank having one end pivotally attached thereto, a drawbar engaging member, an intermediate point of said drawbar engaging member being pivotally attached to an intermediate point on said bell crank, a hydraulic cylinder attached between one end of said bell crank and a point on said drawbar engaging member spaced from said pivotal point to said bell crank, and means to limit the upward movement of said bell crank and adapted to lift the front end of said planer to lift said runners off the ground whereby the rear end thereof is carried by said wheels.

13. The road planer recited in claim 11 wherein means is provided to limit the upward movement of said blade supporting frame.
